UNITED STATES PATENT OFFICE.

EDMUND HARRISON, OF MOUNTAIN VIEW, CALIFORNIA.

IMPROVEMENT IN APPARATUS FOR UNLOADING HAY, &c.

Specification forming part of Letters Patent No. 118,531, dated August 29, 1871.

To all whom it may concern:

Be it known that I, EDMUND HARRISON, of Mountain View, in the county of Santa Clara and State of California, have invented a new and useful Improvement in Apparatus for Unloading Hay, Grain, &c.; and I do hereby declare that the following is a full, clear, and exact description thereof, which will enable others skilled in the art to make and use the same, reference being had to the accompanying drawing forming part of this specification, in which—

Figure 1 is a side view of my improved apparatus. Fig. 2 is a detail bottom view of the receiver. Fig. 3 is a detail side view of the bottom bars of the same.

Similar letters of reference indicate corresponding parts.

My invention has for its object to furnish an improved apparatus for unloading hay, grain, &c., from a wagon-box, header-bed, or other kind of a wagon-box or rack, for stacking hay or grain, and removing grain from a stack or mow to feed a thrashing-machine, and which shall be simple and inexpensive in construction, speedy and effective in operation, and conveniently operated; and it consists in the construction and combination of various parts of the apparatus, as herein-after more fully described.

A is the receiver, which is designed to cover or be spread over the inside of the bed or rack of the wagon, and to be under and around the load. The receiver A may be made of heavy canvas or of a net-work of small ropes. The receiver A is made in two parts, and its edges may be strengthened with ropes. The outer edges of the two parts are attached to side and end bars a^1 , to keep said edges extended. The adjacent edges of the bottom of the receiver A are attached to two bars, a^2 , each of which may be made in two or more parts, jointed to each other at their ends. The bars a^2 I prefer to make in the form of angle-irons, the vertical flanges of which lie along each other, and to the lateral flanges of which the netting or canvas is attached. To the vertical flange of one of the bars a^2 are attached keepers or staples, which pass through holes or slots in the vertical flange of the other bar, and which receive hooks or bolts to lock the said bars a^2 to each other. The lock-bar a^3 , with which the lock-hooks or bolts are connected, extends along the angle of the bar a^2 , and is kept

in place by and works in keepers attached to said bar a^2 . The lock-bar a^3 is jointed wherever the bars a^2 are jointed, and is operated by the lever a^4 , to which one of its ends is pivoted, and which is pivoted to the bar a^2 , to which the lock-bar a^3 is pivoted. The lever a^4 is made of such a length that it may be conveniently operated to lock the parts of the receiver to each other, and to its end is attached the end of a cord, a^5 , which extends down into such a position that it may be conveniently operated to unlock the parts of the receiver and discharge its contents when the receiver has been brought over the place upon which the load is to be deposited. To the side and end bars a^1 , near their ends, are attached ropes a^6 , provided with eyes to hook upon hooks attached to the corners of the wagon-box to keep the receiver extended while receiving the hay or grain. When the loading has been completed these eyes are detached from the wagon-box and are hooked upon hooks attached to the corners of the frame B. Additional ropes a^6 may be attached to the middle parts of the side and end bars a^2 when desired or necessary. The frame B should be made somewhat smaller than the receiver A, and to its central part is attached the end of the hoisting-rope C for raising and lowering the receiver A. D is the derrick-pole or shaft, which should be thirty feet, more or less, in height, and the lower end of which is pivoted to the bed-plate E, which should be staked or spiked to the ground or floor in the place where the hay or grain is to be handled. The upper end of the shaft D is swiveled to a plate, F, to which are attached the upper ends of a sufficient number of guy-ropes, G, to hold the said shaft securely in position. The lower ends of the guy-ropes G are staked to the ground or are attached to other suitable supports. H are the arms of the derrick, the inner ends of which are hinged or jointed to ears attached to the upper parts of the shaft D, so that the outer ends of the arms H may be raised or lowered, as may be desired. I is a rope, the ends of which are attached to the outer ends of the arms H, and which passes through a hole or around a pulley in the upper part of the shaft D. To the middle parts of the arms H are attached the upper ends of the ropes J, the lower ends of which are secured to belaying-cleats or other suitable supports attached to the lower part of the shaft D, so that, by adjusting the

ropes J, the arms H may be adjusted without its being necessary to ascend the shaft D or lower it to adjust the said arms H. The hoisting-ropes C pass over a pulley, K, connected with the outer ends of the arms H, and over a pulley, L, connected with said arms H, but placed further inward or toward the shaft D. The ropes C then pass down and around pulleys M, pivoted to the bed-plate E as near as possible to the foot of the shaft D, and to them is attached the draft.

For stacking hay from the cock or wagon, and for various other purposes, it may be advisable to use a hay-fork, N. In this case a fork, N, should be attached to the end of the hoisting-rope C of each arm H, so that an empty fork may be descending while a loaded fork is ascending; and the two hoisting-ropes C should be continuous, so that the horse, when moving in one direction, may raise one fork, N, and when moving back, or in the other direction, may raise the other fork, and thus need not make a round trip for each fork-load.

Having thus described my invention, I claim as new and desire to secure by Letters Patent—

1. The receiver A $a^1 a^2 a^3 a^4 a^5 a^6$ and frame B, constructed and operating, substantially as herein shown and described, to adapt it to receive the hay or grain and transfer the load bodily, by means of a derrick, to the place where it is to be deposited, as set forth.

2. The jointed bars a^2 , jointed bar or rod a^3 provided with bolts and lever a^4 , in combination with the parts of the netting or canvas of the receiver A, substantially as herein shown and described, and for the purposes set forth.

3. The derrick formed of the shaft or pole D, bed-plate E, swiveled plate F, guy-ropes G, hinged arms H, supporting and adjusting-ropes I and J, hoisting-ropes C, and pulleys K L M, whether the receiver A or fork or forks N be used with said derrick, said parts being arranged and operating substantially as herein shown and described, and for the purposes set forth.

EDMUND HARRISON.
